12 Claims. (Cl. 242—56)

1

The present invention relates to improvements in machines for rewinding of paper sheets.

Paper is used at a large scale in the form of small rolls, such as for example counter rolls, rolls of toilet paper, tapestry, cash register strips, adhesive strips etc. These small rolls are produced in special smaller roll winding machines, which are usually referred to as counter roll machines, rewinding machines, winding machines, reeling machines, small-roll machines etc. Common to all these types of machines is that they are designed for producing smaller paper rolls by rolling or winding or reeling a certain amount of paper onto a rotating spindle from a larger roll usually referred to as a supply roll, often accompanied by a simultaneous division of the paper sheet in the longitudinal direction, so that the supply roll is divided into a number of smaller rolls, which may therefore have the same width or a smaller width than the supply roll and a smaller paper length (meters per roll) or diameter than the supply roll.

The features of the present invention are applicable to all the above mentioned types of machines, and although in the present specification and claims the machine according to the invention is shortly referred to as a rewinding machine, this expression is to be read in a broad sense, so as to comprise machines for any of the above mentioned and similar purposes.

An object of the invention is to provide a machine of the class described, which is substantially or wholly automatic in operation and requires a minimum of attendance.

Another object is to provide an automatic paper rewinding machine, which is of relatively simple construction and yet reliable in operation since it has a high production capacity, undue delays in the operation of the machine are minimized.

A further object is to provide an automatic machine of the class described by which the risk of damaging the paper sheet is minimized.

A still further object is to provide an automatic machine of the class described which has a smooth rewinding spindle and which after each rewinding operation and subsequent severing of the paper sheet provides for a cautious wrapping of the leading end of the sheet supplied, around the spindle and a smooth start of the new rewinding operation.

Further objects as well as the various features of the invention will appear from the following specification read in connection with the drawings, which illustrate an embodiment of a rewinding

2

machine according to the invention. However, the embodiment shown and described is to be regarded merely as an example, and not to be construed as limiting the conception of the invention, the scope of which is laid down in the appendant claims.

In the drawings:

Fig. 1 is a somewhat diagrammatic side view of the machine with parts, including one machine stand, removed for better illustration.

Fig. 2 is a similar front view, partly in section.

Fig. 3 is a top view of the machine with certain parts omitted.

Fig. 4 is a view from the same side as Fig. 1, but at a different stage of operation.

Fig. 5 is a fragmental view of Fig. 4.

In all figures the same reference numerals are used for the same parts.

In the specification and drawings certain parts which are of conventional design and similar to those of ordinary rewinding machines, are not shown and described in full details. This, for example, is the case with the detachable mountings for a rotatable supply roll 29, which mountings comprise a three-part supply roll spindle 18, bearings 19, 20, 21 and 22, clutch 23, brake drum 24, brake band 25, brake lever 26 and weight 27. Of substantially conventional design is also the machine frame which comprises spaced stands 1 and 2 suitably braced, the former being hollow in order to support spaced bearings for various rotatable parts, and the rollers 3, 4 and 5 journaled in the frame for guiding the paper sheet 30 from the supply roll 29 to the rewinding spindle 6.

The rewinding spindle 6 has a smooth cylindrical surface and is supported for free axial and rotational movement by a horizontal composite bearing sleeve 49 journaled in the stand 1 by means of conical roller bearings 52 and 53 permitting rotation but preventing axial movements of the sleeve. Projecting coaxially to the sleeve 49 from a collar 54 on the exterior side of the stand 1 is a servomotor cylinder 45 into which the spindle 6 and the sleeve 49 projects at their rear extremities. Movable within the cylinder 45 is a piston 46 within which a reduced extension of the spindle 6 is free to rotate, but engaged for axial movements with the piston by a pair of conical roller bearings withheld by a nut 47 screw-threaded on said extension. Fixed on the spindle 6 and the sleeve 49 within the cylinder 45 are clutch members 51 and 51' respectively, which in the forward or operative position of the spindle 6 are in mutual engagement for entrain-

ing the spindle 6 in rotation of the sleeve 49, but which are released from such engagement by rearward movement of the spindle with the piston 46.

Rotational movement from the shaft 9 of a motor 7 is imparted through a pulley 10 thereon and a belt 11 to a member or pulley 12 fixed on the sleeve 49 within the stand 1. The belt 11 is passed over tensioning rollers 13 and 14 rockably mounted by means of a shaft 17 in the stand 1. The shaft 17 also carries a ratchet segment 16 engaged by the armature of an electro-magnet 34 for keeping the rollers 13 and 14 in their tensioning position as shown in Fig. 1. The segment 16 carries a hand lever 15, which thus may be used for starting the rotation of the spindle 6 by manual operation. In addition the shaft 17 carries an arm 123 connected by a rod 122 to a cam follower 121 for automatic operation, as will be described later.

Mounted on a bracket on the outside of the stand 1 are an electro-magnet 35, a lever 39 operated thereby and a valve housing 41 for a valve slide 40 adapted to be moved by the lever 39 for alternatively connecting a source (not shown) of pressure fluid such as compressed air to the forward or rear ends of the cylinder 45 through conduits 44 or 47 respectively.

A pawl 42 pivoted on the housing 41 is arranged as shown in Fig. 2 above one end of the lever 39 and adapted in a lifted position to permit free movement thereof and when not so lifted to be withheld by the lever so as not to prevent movement of the lever and valve slide from the position shown, in which fluid pressure is applied to the rear side of the piston 46, to the inverse position. After the lever has moved, the pawl will fall down behind the lever so as to prevent renewed shifting of the valve until the pawl is again lifted.

The armature of the electro-magnet 35 in addition to engaging the lever 39 is also connected through a wire 36, passed over rollers 37, and a spring 38, to the brake band 25 for the supply roll spindle so as to cause braking of the same when operated.

Operating circuits of the electro-magnets 34 and 35 are connected in parallel to the main 33 through front contacts on a relay or magnet switch 32, the magnet coil of which is connected to the mains through a switch 31, so positioned as to be engaged by the periphery of the rewound roll and thus constituting a means sensible to the quantity of paper rewound.

From the foregoing it will be understood that with the switch 31 positioned for being operated when the rewound roll has attained the desired diameter, the operation of the mechanism so far described will be as follows when the machine is started:

After the supply roll 29 has been placed in position and the motor 7 has been started, the paper sheet 30 is placed over the guiding rollers 3, 4 and 5 and placed around the spindle 6 by hand in the usual manner, which spindle is then started for clockwise rotation as viewed in Fig. 1 by lifting the handle 15 manually. By the rotation of the spindle 6, a paper roll 28 will now be formed on the same, the diameter of which increases for each revolution of the spindle. After the desired diameter of the roll 28 has been obtained, the switch 31 will be closed and operate the relay 32. Thereby the electro-magnet 34 is operated, the ratchet segment 16 is released, the belt 11 is slackened, and the rotation of the winding spindle 6 ceases. The operation of the relay

32 also causes operation of the magnet 35, thereby increasing the braking force on the roll 29 so as to stop the same immediately. Hereby it is obtained that the paper sheet 30 will remain tight without curving between the peripheries of the roll 29, the guiding rollers 3, 4 and 5 and the roll 28. Further on operation the magnet 35 will through the lever 39 press the slide 40 in the valve housing 41 to the right, and the pawl 42 resting on the extremity of the lever 39, will now fall down behind the same and lock the slide 40 in this position. Compressed air (or another medium) now flows through the input passage 43, the slide housing 41 and pipe 44 to the left hand side of the piston 46 in the cylinder 45, while the air to the right of the piston is passed into free air through pipe 47 and the slide housing 41.

By the movement of the piston 46 to the right, the clutch 51, 51' is disconnected, the spindle 6 is entrained so far that the extremity of the spindle passes a short distance into the sleeve 49, and the roll 28 is released from the spindle, disengaging the switch 31 which therefore through relay 32 releases the magnets 35 and 34. However, the pawl 42 keeps the slide 40 in the same position so that the spindle 6 remains within the sleeve 49.

To receive the roll 28 and move the same transversely out of the path of the rewinding spindle 6 after the latter has been withdrawn, a cradle-like supporting structure is provided, which consists of two rollers 55 and 56 extending parallel to the spindle 6 and interconnected by links 60 at the extremity of levers 59 keyed to a shaft 61 which is journaled in the stand 1 and likewise is parallel to the spindle 6. Keyed to the shaft 61 is also a sloping frame-like guiding member 58 for a running weight 57 which by its weight in the position shown in Fig. 1 tends to move the shaft 61 anti-clockwise as viewed in Fig. 1, thereby keeping the supporting structure 55, 56, 59, 60 in an upper position just underneath the roll 28 being rewound. To a lever 63 keyed to the shaft 61 is connected a rod 64 which is guided in a bearing 65 on the stand 1 and in a bifurcation at its lower extremity carries a cam follower 66. A shoulder formed by the said bifurcation on the rod 64 bears, in the position shown in Fig. 1, against the bearing 65, thereby limiting anti-clockwise rotation of the shaft 61. In this position the follower 66 is situated a short distance above the highest portion of a corresponding cam 67 keyed to a cam shaft 68 journaled in the stand 1.

A cam 62 on one of the levers 59 is arranged for closing a switch 69 on clockwise rotation of the shaft 61 before the follower 66 contacts the cam 67. The switch 69 is connected in the operating circuit of a magnet switch or relay 70 in the operating circuit of an electro-magnet 80, which, when operated, through a link 81, lever 82 and shaft 83 engages a clutch 85 connecting a pulley 87 to a worm gear 86. The pulley 87 is connected by a belt to a pulley 8 on the shaft 9 of the motor 12, and the worm gear 86 is connected through a shaft 88 and conical pinions 89 and 90 to the cam shaft 68, whereby the speed of the motor is geared down very considerably, so that the speed of the cam shaft will be for example one revolution in two seconds.

The frame or guide 58 is connected at a point to the right of the shaft 61, as viewed in Fig. 1, to one end of a wire 91, which is passed over rollers 92 and at its other end is connected to the pawl 42.

Thus it will be understood that on withdrawal of the spindle 6 as described above, the roll 28 will fall down onto the rollers 55 and 56 and by its own weight outweigh the running weight 57, thereby causing clockwise rotation of the shaft 61 whereby the cam 62 operates the switch 69 for operating the clutch 85 through the switch 70, magnet 80 and the members 81—84, thereby starting slow rotation of the cam shaft 68 from the motor 7 through the pulley 8 and the members 86—90. The rotation of the cam shaft is assumed to take place in a clockwise direction as viewed in Figs. 1 and 4. During the first part of this rotation—about one-quarter of a revolution—after the follower 66 has engaged the cam 67, the shaft 61 is turned clockwise following the curvature of the cam 67 until a dwell on this cam is attained, corresponding to the position of the members 55—64 shown in Fig. 4. During this movement the slope of the guide 58 is reversed so that the weight 57 runs to a position in which it adds to the weight of the roll 28. Also, due to the rotation of the arms 59, the roll 58 is lowered and thereby moved out of the path of the spindle to a position in which the portion of the sheet 30 extending between the roll 28 and the guiding roller 5 faces the path of the spindle 6 as shown to the right in Fig. 5, and the support 55, 56, 60 for the roll is turned to a sloping position in which the roll 28 tends to roll off in a clockwise direction onto a sloping table 104, but is withheld by the taught unsevered sheet connecting the same to the supply roll 29. Further, as soon as during this movement of the shaft 61 the top of the roll 28 has left the bottom of the path of the spindle 6, the wire 91, being tightened, lifts the pawl 42, the spring 38 acting on the armature of the magnet 35 pulls the slide 40 to the left, the compressed air enters the cylinder to the right of the piston 46, and the spindle is pushed forward into operating position. By this arrangement it is obtained that the spindle 6 cannot interfere with the roll 28.

On return of the spindle 6 to operative position, the clutch member 51 engages the member 51', but the spindle does not yet start rotation, the pulley 12 being not operatively connected to the pulley 10.

A shaft 97 journalled on the top of the stand 1 and extending parallel to the spindle 6 carries substantially L-shaped spaced levers 98, 99 interconnected at their free extremities by a slotted hollow tube or yoke 100, likewise extending parallel to the spindle 6 and capable of being moved transversely to the spindle in a path just below the latter. The shaft 97 is connected by a lever 96 to a rod 95 which is guided in bearings (not shown) on the stand 1 and at its lower end carries a cam follower 94. A spring 126 acting on the rod 95 keeps the follower 94 in contact with a cam 93 so positioned on the shaft 68 that during the first part of the revolution of the cam shaft just described, the follower 94 contacts a lower dwell thereon, whereby the yoke 100 is held in a position outside the path of the roll 28 and at the exterior side of the sheet 30 extending between the latter and the roller 5, in which position the slot 101 in the yoke 100 faces the sheet. A rising portion of the cam 93 followed by a higher dwell, causes the shaft 97 on lowering of the cradle 55, 56, 60 and return of the spindle 6 to its operative position, to turn clockwise, thereby swinging the levers 98, 99 with the yoke 100 to the left causing the latter to engage the sheet and push or press the same into a loop be-

tween the spindle 6 and the roll 28, as shown in Fig. 4 and to the left in Fig. 5, whereby the sheet will partly enclose the spindle, the roll being thereby slightly unwound and turned anti-clockwise on the rollers 55 and 56.

Freely rotatable in bearings supported by resilient arms 115, 116 and 117, 118 respectively, from the levers 98, 99 rubber coated rollers 113 and 114 are provided for pressing the sheet 30 against the side and bottom surfaces respectively, of the spindle 6 during the later part of the said movement of the shaft 97.

A stationary cutting knife or severing member 102 fixed to the machine frame by means not shown, is provided ahead of the yoke 100 and in such a position in the path thereof that in the innermost position of the yoke, as defined by the higher dwell on the cam 93, the knife 102 enters the slot 101 therein. The knife 102 as well as the yoke 100 and the slot 101 are all somewhat longer than corresponding to the width of the sheet 30. A glue roller 103 rotatably supported from the machine frame and having glue applied to it by clockwise rotation thereof by means not shown (such as by transmission from the cam shaft 68) is provided underneath the knife 102 in such a position as to be tangent to the bottom side of the yoke 100 in the innermost position of the latter.

Journalled in bearings on the levers 98 and 99 is a cross bar 109 on which a shelter plate 110 is supported by plate springs 111. Rigidly connected to the cross bar 109 is a gear segment 108 which normally rests on a stop 125 on the lever 99, in which position the shelter plate 110 lies flat between the levers 98 and 99 ahead of the roller 114 and behind the yoke 100. The outer portion of the plate 110 is supported by plate springs 111. The outer portion of the plate 110 is curved towards the side facing the spindle 6 with a curvature corresponding to that of the latter, and carries small freely rotatable pressure rollers 112 and a resiliently mounted pressure bar 119. A rack 107 guided in bearings on the stand 1 carries in its lower extremity a cam follower 106 cooperating with a cam 105 on the cam shaft 68 and held in contact therewith by a spring 124 acting on the rack 107. The rack is so positioned that it meshes with the segment 108 in the innermost position of the levers 98 and 99.

The cam 105 and a further cam 120 on the cam shaft 68 are so shaped and positioned that while the follower 94 is still on the higher dwell of the cam 93, the rack 107 will be raised and again lowered and the cam 120 will engage the follower 121 on the rod 122 previously referred to so as to turn the shaft 17 anti-clockwise.

The operation of the structures just referred to, which are all controlled by the rotation of the cam shaft, is as follows:

When the follower 94 approaches the higher dwell of the cam 93 and consequently the levers 98 and 99 approach their innermost position, the rollers 113 and 114 keep the sheet 30 in engagement with the spindle 6, the segment 108 engages the rack 107, the knife 102 enters the slot 101 thereby severing the sheet 30, and the glue roller 103 contacting the sheet just behind the severing line applies an adhesive layer to the tail end of the sheet extending from the roll 28.

Subsequently to the severing operation, the roll 28 will roll off from its supports 55, 56 onto the inclined table 104. It will be appreciated that when doing so it will turn in a rewinding direction so that the tail end of the sheet will

automatically be wrapped around it and, due to the adhesive layer on its interior surface, will automatically be stuck to the roll.

On further rotation of the cam shaft, while the levers 98 and 99 remain stationary, the rack 107 rises, turning the segment 108 with the bar 109 and the shelter plate 110 clockwise, whereby the leading end of the sheet behind the severing line is wrapped smoothly around the spindle 6 by the plate 110 with the rollers 113 which resiliently press the sheet against the spindle. The uttermost end of the sheet is resiliently pressed into the nip between sheet and spindle by the bar 119.

By further rotation of the cam shaft, the cam 120 turns the shaft 17 anti-clockwise, moving the tensioning rollers into operative engagement with the belt 11 and the segment 16 into locking engagement with the armature of the magnet 34. The rising curve of the cam 120 has a slight slope, so that the belt is cautiously tightened causing a slow slipping start of the pulley 12 and hence of the spindle 6. The extremity of the paper sheet 30 under the bar 119 is pinched in the nip, and the sheet having thus been wrapped smoothly around the starting spindle, is neatly entrained and continues to wind itself around it in a new rewinding operation.

After a few revolutions of the spindle 6, the cam shaft 68 has advanced so far that the shelter plate 110 is withdrawn by the spring 124, the rack 107 and gear segment 108 into engagement of the latter with the stop 125, and the levers 98 and 99 are forced back to the starting position by the spring 126. By the last quarter of the revolution of the cam shaft the arm 67 lifts the lever 59, the running weight rolls to the left, whereby the switch 69 and thereby the switch 70 and the clutch 85 are released and the cam shaft is stopped in the starting position, while the pawl 42 is lowered onto the lever 39. The spindle 6 continues its rotation until the roll 28 again engages the switch 31, and the process is repeated automatically so long as there is paper left on the unwinding spindle 18.

In all places where the present specification refers to "the roll 20" this may also be read "the rolls 28," since the present machine, like other winding machines, may be provided with circular knives which divide the paper sheet longitudinally, or the supply roll may be divided beforehand.

By connecting the switch 31 (Fig. 1) with an electric measuring clock driven from a pilot roller in contact with the paper, rolls of a predetermined paper length may be obtained, if desired.

Instead of one single winding spindle supported at one end, it is also possible to use two spindles which are supported co-axially opposite each other and are displaced in opposite directions.

The automatic operation of the described machine may, if desired, be made still more complete; thus a device, for example driven from the cam shaft 61 through a reduction gearing may be provided for displacing the weight 21 on the lever of the supply roll brake a small distance inwards during each cycle of operation to maintain equal tensioning of the paper sheet. Likewise a device which may also suitably be controlled from the cam shaft, may be provided for keeping this brake lifted until the winding spindle has started pulling, in order that the start may be effected as easily as possible and

with the least possible stretching of the paper sheet.

I claim:

1. A paper rewinding machine comprising means for rotatably supporting a supply roll, a spindle for rewinding a paper sheet unwound from said supply roll, guiding means for said spindle permitting rotational and axial movements but preventing transverse movements thereof, means for withdrawing said spindle axially from an operative to an inoperative position and again returning it to said operative position, means for rotating said spindle in said operative position for performing a rewinding operation, displacing means adapted on withdrawal of said spindle to receive a rewound roll therefrom and move the same transversely to a position in which it is situated outside the path of the spindle and in which the interior side of the paper sheet behind the rewound roll faces said path, and a wrapping and cutting mechanism which comprises a cutting member and a member parallel to the spindle and movable transversely thereto, which latter member is adapted on removal of the rewound roll from the path of the spindle and returning of the spindle to operative position, to engage the paper sheet between spindle and roll from the outside and move the sheet into contact with the spindle for a new rewinding operation and into operative engagement with said cutting member.

2. A paper rewinding machine comprising means for rotatably supporting a supply roll, a spindle for rewinding a paper sheet unwound from said supply roll, guiding means for said spindle permitting rotational and axial movements but preventing transverse movements thereof, means for withdrawing said spindle axially from an operative to an inoperative position and again returning it to said operative position, means for starting rotation of said spindle on its return to said operative position, means sensitive to the amount of paper rewound on said spindle for interrupting such rotation on the completion of a rewinding operation, displacing means adapted on withdrawal of said spindle to receive a rewound roll therefrom and move the same transversely to a position in which it is situated outside the path of the spindle and in which the interior side of the paper sheet behind the rewound roll faces said path, and a wrapping and cutting mechanism which comprises a cutting member and a member parallel to the spindle and movable transversely thereto, which latter member is adapted on removal of the rewound roll from the path of the spindle and returning of the spindle to operative position, to engage the paper sheet between spindle and roll from the outside and move the sheet into contact with the spindle for a new rewinding operation and into operative engagement with said cutting member.

3. A paper rewinding machine comprising means for rotatably supporting a supply roll, a spindle for rewinding a paper sheet unwound from said supply roll, guiding means for said spindle permitting rotational and axial movements but preventing transverse movements thereof, means for withdrawing said spindle axially from an operative to an inoperative position and again returning it to said operative position, driving means for rotating said spindle, means for connecting said spindle to said driving means on the arrival of the spindle to said operative position and for disconnecting said

spindle from said driving means on the completion of a rewinding operation, displacing means adapted on withdrawal of said spindle to receive a rewound roll therefrom and move the same transversely to a position in which it is situated outside the path of the spindle and in which the interior side of the paper sheet behind the rewound roll faces said path, and a wrapping and cutting mechanism which comprises a cutting member and a member parallel to the spindle and movable transversely thereto, which latter member is adapted on removal of the rewound roll from the path of the spindle and returning of the spindle to operative position, to engage the paper sheet between spindle and roll from the outside and move the sheet into contact with the spindle for a new rewinding operation and into operative engagement with said cutting member.

4. A paper rewinding machine comprising means for rotatably supporting a supply roll, a spindle for rewinding a paper sheet unwound from said supply roll, guiding means for said spindle permitting rotational and axial movements but preventing transverse movements thereof, means for withdrawing said spindle axially from an operative to an inoperative position and again returning it to said operative position, driving means comprising a rotating member surrounding said spindle, a first clutch member fixed to said spindle outside said guiding means, a second clutch member fixed to said rotating member and adapted to be engaged and disengaged by said first clutch member by the movement of the spindle to and from said operative position respectively, displacing means adapted on withdrawal of said spindle to receive a rewound roll therefrom and move the same transversely to a position in which it is situated outside the path of the spindle and in which the interior side of the paper sheet behind the rewound roll faces said path, and a wrapping and cutting mechanism which comprises a cutting member and a member parallel to the spindle and movable transversely thereto, which latter member is adapted on removal of the rewound roll from the path of the spindle and returning of the spindle to operative position, to engage the paper sheet between spindle and roll from the outside and move the sheet into contact with the spindle for a new rewinding operation and into operative engagement with said cutting member.

5. A paper rewinding machine comprising means for rotatably supporting a supply roll, a brake for said supply roll, a spindle for rewinding a paper sheet unwound from said supply roll, guiding means for said spindle permitting rotational and axial movements but preventing transverse movements thereof, means for withdrawing said spindle axially from an operative to an inoperative position and again returning it to said operative position, means for starting rotation of said spindle on its return to said operative position, means comprising an electric switch sensitive to the amount of paper rewound on said spindle, means comprising an electromagnet controlled by said switch for operating said brake, starting withdrawal of said spindle and interrupting said rotation on the completion of a rewinding operation, displacing means adapted on withdrawal of said spindle to receive a rewound roll therefrom and move the same transversely to a position in which it is situated outside the path of the spindle and in which the interior side

of the paper sheet behind the rewound roll faces said path, and a wrapping and cutting mechanism which comprises a cutting member and a member parallel to the spindle and movable transversely thereto, which latter member is adapted on removal of the rewound roll from the path of the spindle and returning of the spindle to operative position, to engage the paper sheet between spindle and roll from the outside and move the sheet into contact with the spindle for a new rewinding operation and into operative engagement with said cutting member.

6. A paper rewinding machine comprising means for rotatably supporting a supply roll, a spindle for rewinding a paper sheet unwound from said supply roll, driving means comprising a rotating member surrounding said spindle, a servomotor comprising a stationary cylinder coaxial to said spindle, a piston within said cylinder and connected to the spindle for moving the same axially, means including a control valve for supplying pressure-fluid to said cylinder on alternate sides of said piston for withdrawing the spindle axially from an operative position on completion of a rewinding operation and again returning it to said operative position, a first clutch member fixed to said spindle within said cylinder, a second clutch member within said cylinder and fixed to said rotating member and adapted to be engaged and disengaged by said first clutch member on movement of the spindle to and from said operative position respectively, displacing means adapted on withdrawal of said spindle to receive a rewound roll therefrom and move the same transversely to a position in which it is situated outside the path of the spindle and in which the interior side of the paper sheet behind the rewound roll faces said path, and a wrapping and cutting mechanism which comprises a cutting member and a member parallel to the spindle and movable transversely thereto, which latter member is adapted on removal of the rewound roll from the path of the spindle and returning of the spindle to operative position, to engage the paper sheet between spindle and roll from the outside and move the sheet into contact with the spindle for a new rewinding operation and into operative engagement with said cutting member.

7. A paper rewinding machine comprising means for rotatably supporting a supply roll, a spindle for rewinding a paper sheet unwound from said supply roll, guiding means for said spindle permitting rotational and axial movements but preventing transverse movements thereof, means for withdrawing said spindle axially from an operative to an inoperative position and again returning it to said operative position, means for rotating said spindle in said operative position for performing a rewinding operation, displacing means for rewound rolls, which means comprises a supporting device so located that on withdrawal of the spindle it receives the roll rewound thereon, and mounted for moving transversely with the roll resting thereon, to a position in which the roll is situated outside the path of the spindle and tends to roll off from said supporting device in a rewinding direction, and in which the paper sheet behind said roll is taut and the interior side thereof faces said path, and a wrapping and cutting mechanism which comprises a cutting member and a member parallel to the spindle and movable transversely thereto, which latter member is adapted on removal of the rewound roll from

the path of the spindle and returning of the spindle to operative position, to engage the paper sheet between spindle and roll from the outside and move the sheet into contact with the spindle for a new rewinding operation and into operative engagement with said cutting member.

8. A paper rewinding machine comprising means for rotatably supporting a supply roll, a brake for said supply roll, a spindle for rewinding a paper sheet unwound from said supply roll, driving means comprising a rotating member surrounding said spindle, a servomotor comprising a stationary cylinder coaxial to said spindle, a piston within said cylinder and connected to the spindle for moving the same axially, means including a control valve for supplying pressure fluid to said cylinder on alternate sides of said piston for withdrawing the spindle axially from an operative position on completion of a rewinding operation and again returning it to said operative position, a first clutch member fixed to said spindle within said cylinder, a second clutch member within said cylinder and fixed to said rotating member and adapted to be engaged and disengaged by said first clutch member on movement of the spindle to and from said operative position respectively, displacing means for rewound rolls, which means comprises a supporting device so located that on withdrawal of the spindle it receives the roll rewound thereon, and mounted for moving transversely with the roll resting thereon, to a position in which the roll is situated outside the path of the spindle and tends to roll off from said supporting device in a rewinding direction, and in which the paper sheet behind said roll is taut and the interior side thereof faces said path, sensitive means so positioned with respect to said spindle and said supporting device that it is engaged by the periphery of a rewound roll thereon so as to adopt an operative position on completion of a rewinding operation and an inoperative position on transverse movement of said roll by said displacing means, operating means, controlled by said sensitive means and adapted in the operative position of said sensitive means to operate said brake and to position said control valve for withdrawal of the spindle by said piston and in the operative position of said sensitive means to release said brake and position said control valve for returning the spindle to the operative position thereof, locking means for delaying said latter positioning of the control valve until said roll has been removed from said path, and a wrapping and cutting mechanism which comprises a cutting member and a member parallel to the spindle and movable transversely thereto, which latter member is adapted on removal of the rewound roll from the path of the spindle and returning of the spindle to operative position, to engage the paper sheet between spindle and roll from the outside and move the sheet into contact with the spindle for a new rewinding operation and into operative engagement with said cutting member.

9. A paper rewinding machine comprising means for rotatably supporting a supply roll, a spindle for rewinding a paper sheet unwound from said supply roll, guiding means for said spindle permitting rotational and axial movements but preventing transverse movements thereof, means for withdrawing said spindle axially from an operative to an inoperative position and again returning it to said operative position, means for rotating said spindle in said

operative position for performing a rewinding operation, displacing means adapted on withdrawal of said spindle to receive a rewound roll therefrom and move the same transversely to a position in which it is situated outside the path of the spindle and in which the interior side of the paper sheet behind the rewound roll faces said path; and a wrapping and cutting mechanism which comprises sheet engaging means comprising a yoke parallel to the spindle and removable transversely thereto and having a longitudinal slot and adapted on removal of said roll by said displacing means and return of said spindle to operative position to press said sheet inwards between spindle and roll so as to form a loop engaging the spindle on a part of the periphery thereof, a stationary cutting knife registering with said slot in the innermost position of said yoke for severing said sheet, said sheet engaging means further comprising resilient pressing means for keeping the sheet in engagement with said spindle during cutting.

10. A paper rewinding machine comprising means for rotatably supporting a supply roll, a spindle for rewinding a paper sheet unwound from said supply roll, guiding means for said spindle permitting rotational and axial movements but preventing transverse movements thereof, means for withdrawing said spindle axially from an operative to an inoperative position and again returning it to said operative position, means for rotating said spindle in said operative position for performing a rewinding operation, displacing means adapted on withdrawal of said spindle to receive a rewound roll therefrom and move the same transversely to a position in which it is situated outside the path of the spindle and in which the interior side of the paper sheet behind the rewound roll faces said path, a wrapping and cutting mechanism which comprises sheet engaging means comprising a yoke parallel to the spindle and removable transversely thereto and having a longitudinal slot and adapted on removal of said roll by said displacing means and return of said spindle to operative position to press said sheet inwards between spindle and roll so as to form a loop engaging the spindle on a part of the periphery thereof, a stationary cutting knife registering with said slot in the innermost position of said yoke for severing said sheet, said sheet engaging means further comprising resilient pressing means for keeping the sheet in engagement with said spindle during cutting, and a glue roller parallel to said spindle and so located adjacent said cutting knife that in the innermost position of said yoke, the sheet is firmly pressed against said roller by said yoke so as to receive an adhesive coating ahead of the cutting line.

11. A paper rewinding machine comprising means for rotatably supporting a supply roll, a spindle for rewinding a paper sheet unwound from said supply roll, guiding means for said spindle permitting rotational and axial movements but preventing transverse movements thereof, means for withdrawing said spindle axially from an operative to an inoperative position and again returning it to said operative position, slipping means for slowly starting rotation of said spindle on its return to said operative position, means for interrupting rotation of said spindle on the completion of a rewinding operation, displacing means adapted on withdrawal of said spindle to receive a rewound roll therefrom and move the same transversely

13

to a position in which it is situated outside the path of the spindle and in which the interior side of the paper sheet behind the rewound roll faces said path, and a wrapping and cutting mechanism which comprises sheet engaging means comprising a yoke parallel to the spindle and removable transversely thereto and having a longitudinal slot and adapted on removal of said roll by said displacing means and return of said spindle to operative position to press said sheet inwards between spindle and roll so as to form a loop engaging the spindle on a part of the periphery thereof, a stationary cutting knife registering with said slot in the innermost position of said yoke for serving said sheet, said sheet engaging means further comprising a resilient guiding and pressing device adapted during the slow start of the spindle to wrap the forward portion of the sheet remaining after the severing operation entirely around the spindle after cutting and after the spindle has

started pulling to return to an inoperative position before said yoke leaves the cutting position.

12. A paper rewinding machine as claimed in claim 11 and in which said guiding and pressing device comprises resilient means for making the outermost end of the sheet engage the paper sheet in the nip ahead of the spindle with a light pressure.
